UNITED STATES PATENT OFFICE.

GRANT HEEBNER, OF INDIANAPOLIS, INDIANA.

UNIVERSAL COPYHOLDER.

Application filed November 30, 1923. Serial No. 677,645.

This invention relates to apparatus for the use of copyists or those who transcribe or copy matter written or printed on sheets of paper, the invention having reference more particularly to apparatus for holding and shifting copy and indicating to the copyist the place where the lines of the copy should be successively seen, as an aid in efforts to insure the accurate copying, particularly to avoid repetitions and omissions, while tending to aid the copyist in efforts to copy rapidly.

An object of the invention is to provide an improved mechanical copy holder and guide for the use of copyists, stenographers and others, and especially those who copy on typewriting machines, or transcribe on such machines such matter as may have been written or printed on paper.

Another object is to provide an improved copy holder and guide to enable operators of typewriting machines to rapidly and accurately make copies of matter written or printed on sheets of paper.

A further object is to provide an improved and inexpensive transferable copy holder of the above-mentioned character, which shall be of such construction as to permit a typist to have copy most conveniently arranged for observation either above or at either side of a typewriter, and permit the copy to be rapidly moved as the work proceeds.

A still further object is to provide an improved copy holder and guide which shall be of such construction as to permit of manufacture of stock material, and which shall be capable of being readily transferred and adjusted to different positions as may be desired by different users, and which shall be durable, convenient and economical in use.

With the above-mentioned and other objects in view, the invention consists in novel apparatus whereby to hold and shift copy sheets and to guide the eyes of the copyist to the lines of copy or original matter required to be copied or transcribed on a typewriting machine or otherwise; and the invention consists also further in the novel parts and combinations and arrangements of parts as hereinafter particularly described and further set forth in the claims appended hereto.

Referring to the drawings,—Figure 1 is a side elevation of apparatus constructed substantially in accordance with the inven-

tion and arranged in connection with a typewriting machine shown mainly by dotted lines; Fig. 2 is a perspective view of the supporting stand or frame of the apparatus adapted to hold the copy above the typewriting machine; Fig. 3 is a perspective view of the more essential assembly of the apparatus whereby to support copy on a desk or a table adjacent to a typewriting machine; Fig. 4 is a vertical longitudinally central section, partially broken away, of the assembly shown in Fig. 3, but on an enlarged scale; Fig. 5 is a transverse section of parts of the apparatus approximately on the line V—V in Fig. 4; Fig. 6 is a fragmentary elevation partly in section on the line VI—VI in Fig. 5; Figs. 7, 8 and 9 are fragmentary sectional details showing on an enlarged scale various features of the apparatus; and, Fig. 10 is a fragmentary detail on an enlarged scale of means for expeditiously shifting copy on the holder.

Similar reference characters in the different figures of the drawings indicate corresponding elements or features of construction herein referred to in detail.

A typewriting machine 1 is shown which will be readily recognized as one style of many similar machines, each having a key board frame 2, the main frame of the machine usually having a rear lower rail 3.

The copy holder proper includes a portable frame which preferably is composed of sheet metal and comprises a base plate 4 that is oblong in plan, and end members 5 and 6 that are integral with the narrower ends of the base plate. The end members are provided with journal bearings 7 and 7' respectively that are formed integrally with the members. A preferably hollow cylinder is provided which preferably is formed of rolled sheet metal and preferably has a longitudinal slot 9 therein, the cylinder having supporting heads 10 and 11 provided in the inner side thereof with annular grooves or recesses 12 and 12' respectively that receive the ends of the cylinder. The heads preferably are composed of sheet metal and are provided with sockets 13 and 13' respectively that are pressed up from the material, threaded nuts 14 and 14' being arranged in the sockets respectively, each nut being retained in place by means of clips 15 stamped from the material and turned over against the nut. Two shafts 16 and 16' are provided, and may be alike, the shafts having

journals 17 and 17' that are screwed into the nuts and rotatably supported in the journal bearings 7 and 7' respectively. The shafts have stems 18 and 18' thereon to which hand-wheels 19 and 19' are fixed, and each stem preferably has a socket 20 therein provided with a set-screw 21, to permit rotation of the cylinder by mechanical means. Preferably the wall of the cylinder supports a guide plate 22 that extends inwardly from one side of the slot 9, the plate having a stop plate 23 thereon that is supported opposite to the slot. A metallic guide plate 24 is fixed to the normally rear portion of the base plate 4, the plate preferably being integral with the rear edge of the base plate and extending upwardly at an inclination over the major portion of the base plate towards the cylinder and thence upward and gradually to the surface of the cylinder higher than the axis of rotation of the cylinder, the guide having a horizontal guide edge 25. Preferably the guide plate has two rollers 26 and 26' rotatably mounted in openings therein to roll against paper on the cylinder. Preferably the normal forward edge of the base plate 4 has a lip 27 struck up thereon against which cards may be placed so as to lean against the higher portion of the guide plate 24. The copy holder proper, as above described may be readily moved from place to place and can stand with its base on a desk or table at either side of a typewriting machine, or elsewhere, and the cylinder may be rotated by means of one of the hand-wheels connected therewith.

Preferably the copy holder is provided with a stand to adjustably support it above or higher than a typewriting machine, and to attain this end the frame that supports the cylinder is provided with suitable pivots, the end members 5 and 6 preferably having sockets 28 and 28' thereon respectively, each socket having a nut 29 secured therein by means of clips 30 struck up from the metal of the end members. The sockets are arranged in proximity to the normal forward portion of the base plate 4, and pivot screws 30 and 31 are connected with the nuts respectively. The stand comprises a standard which preferably is composed of two parts 32 and 33 arranged together and having laterally extending foot members 34 and 35 fixed thereto respectively for support on the desk or table, and also a relatively adjustable foot member 36 having a head portion 37 that extends upwardly to the standard and is adjustably secured thereto by means of a binding screw 38, permitting the stand to be adjusted so as to be inclined relatively to the foot member 36. It is designed that the foot member 36 shall be placed under the rearward portion of the typewriting machine, and the foot member has a screw 39 vertically fixed thereto on which is a

flanged nut 40 that can be arranged so as to be partially under the rear rail 3 of the typewriting machine, permitting the nut to be screwed upward to force the flange thereof against the under side of the rail whereby to secure the foot member between the rail and the top of the desk or table. Preferably the foot members 34 and 35 are provided with rubber cushions 41 and 41' respectively, the member 36 having a similar cushion 41", to prevent marring the desk or table supporting the stand and tending to prevent slipping of the stand thereon. The upper portion of the standard parts 32 and 33 have off-set jaw blades 42 and 43 thereon, and a frame is provided which preferably comprises two alining transverse members 44 and 45 having relatively angular head members 46 and 47 secured together by means of a rivet 48 to constitute a main arm that is arranged between the jaw blades and pivotally connected therein by means of a pivot bolt 49 that is screwed into one of the blades so as to be removable. Members 44 and 45 have arms 50 and 51 fixed thereon respectively which have pivot holes 52 and 52' respectively to receive the pivot screws 31, 31', when the end members 5 and 6 of the portable frame are arranged between the arms. The pivot screws may be slackened to permit the tilting of the frame in adjusting the cylinder and the guide edge 25 to suit the range of the vision of the copyist. The frame is normally supported adjustably by means of a clamp plate 53 which is guided on the standard so as to be adjusted vertically and is provided with a vertical slot 54 in which is arranged a binding screw 55 that is screw-threaded into the standard, the clamp plate having a stop projection 56 thereon upon which the pivotally supported head member of the frame is further supported. The arms 50 and 51 support the holder cylinder conveniently above the typewriting machine and may be swung upward and rearward to carry the cylinder out of the way when not needed.

For facilitating the rapid turning of the holder cylinder to roll the copy paper thereon, preferably a suitable frame 57 is provided which may be variously supported, the frame preferably having a hanger member 58 thereon adapted to rest upon the frame member 2 of the typewriting machine, the hanger member having a spring clip 59 thereon arranged opposite to the frame 57 to engage the inner side of the frame member 2, to removably secure the frame 57 to the typewriting machine so as to be convenient to the operator. A hand-wheel 60 is arranged in the frame 57 and has a spindle 61 that is journaled in the frame, and a flexible shaft 62 is connected to the spindle and also to the socket 18 or 18', as may be more convenient to the operator, depending upon the

position of the portable holder frame, whether supported on the stand or directly on the typewriter desk.

In practical use a sheet of paper containing matter to be copied or transcribed is inserted between the guide plate 24 and the cylinder 8 and pushed gently against the rollers 26 and 26', after which the cylinder is rotated so as to cause rotation of the 10 rollers, the cylinder and rollers together drawing the paper partially about the cylinder until the uppermost line of the copy passes slightly above the guide edge 25 where it may be seen by the copyist. As the 15 cylinder is periodically turned to shift the copy the sheet passes over the top of the cylinder and downwards behind it until the head end of the sheet makes contact with the incline plate 24 and is guided downwardly thereon and off from the frame, being readily removable after the lower end 20 of the sheet has passed from the guide edge 25. In some cases it is preferable that the copy sheet be rolled about the cylinder, in 25 which case the head end of the sheet is inserted into slot 9 and to the stop plate 23, after which the sheet is pressed down by hand on the surface of the cylinder while the cylinder is rotated until the uppermost 30 line of copy is carried slightly above the guide edge 25, the lower portion of the sheet being permitted to rest upon the guide plate 24 below the cylinder until carried upward and over the cylinder by the repeated turning 35 of the cylinder. A long copy sheet finally becomes wrapped about the cylinder, and when no longer needed it is readily unwrapped upon rotation of the cylinder and withdrawn from the slot. The cylinder obviously may be turned by means of either one 40 of the hand-wheels provided for the purpose as above explained. The various adjustments provided for are made as may be desired, depending upon the situation and conditions of operation of the apparatus comprised in the invention.

Various mechanical expedients, as may be found to be desirable in using the apparatus, have been omitted from the description 50 but may readily be supplied in construction, such as guides to direct the movement of the copy sheet as it advances over the cylinder. Also the hand-wheel 60 or other device for operating and controlling the cylinder may 55 be located elsewhere than on the typewriter, especially when copying is not done on a machine; and, various means other than the flexible shaft, shown as being one of a simple type of device, may be adopted for directly rotating the cylinder intermittently.

What is claimed as new, is:—

1. A copy holder including a frame comprising a flat base plate and two upright-end members, the end members having each a 65 journal-bearing, a non-continuous hollow

cylinder, two heads secured to the ends respectively of the cylinder and having each a central socket, two threaded nuts secured in the sockets respectively, two shafts screwed into the nuts respectively and rotatably supported by the journal-bearings respectively, and a device connected to one of the shafts to rotate the cylinder. 70

2. A copy holder including a stand comprising a standard having two opposite foot members fixed thereto, a holding foot member connected to the standard for pivotal adjustment relatively to the standard, a screw vertically secured to the holding foot and having a flanged nut thereon, and a head 75 frame adjustably connected to the standard and having two arms thereon; a portable frame tiltingly supported by the arms, a cylinder rotatably supported by the portable frame, a guide connected to the portable 80 frame and extending gradually to the surface of the cylinder, and a device for rotating the cylinder having operative connections therewith. 85

3. In a copy holder, the combination of 90 a frame base plate and two upright end members integral with the plate, said members having each a journal-bearing, a hollow cylinder having a longitudinal slot therein, two heads provided on the inner sides thereof with annular grooves receiving the ends of the cylinder, each head having a central socket, two threaded nuts secured in said sockets respectively, two shafts having journals that are screwed into said nuts and supported by said journal-bearings respectively, each shaft being provided with an operating stem, a guide plate fixedly connected to said cylinder and extending inwardly from one side of said slot, a stop plate fixed 100 to the end of said guide plate, and a guide plate fixedly connected to said base plate and extending upwardly at an inclination and thence gradually to said cylinder. 105

4. In a copy holder, the combination of 110 a portable frame comprising a flat base plate and two upright end members, the end members having each a journal bearing, one edge of the base plate having an upturned lip thereon, a cylinder having two heads provided each with a central socket and a threaded nut secured in the socket, two shafts having journal portions and being screwed into said nuts respectively, said portions being rotatably supported by said bearings respectively, a hand-wheel fixed to one of said shafts, and a guide plate fixedly connected to the opposite edge of said base plate and extending upwardly at an inclination and thence gradually to said cylinder. 115 120

5. In a copy holder, the combination with 125 a cylinder having journal shafts and a hand-wheel fixed to one of the shafts, of a frame comprising a base plate and two upright end members on opposite ends of the plate, 130

the end members having journal bearings rotatably supporting the journal shafts, one edge of the base plate having an upturned lip thereon, and a guide plate fixedly connected to the opposite edge of the base plate and extending upwardly at an inclination towards the cylinder and thence curved gradually to the cylinder, the guide plate having two rollers mounted thereon to cooperate with the cylinder to roll a copy sheet thereon.

6. In a copy holder, the combination with a portable frame having two pivot screws detachably connected thereto, and a cylinder rotatably mounted on the frame, of a stand comprising a standard having two oppositely extending foot members, a relatively an-

gular foot member having an inclined portion adjustably secured to the standard above the two foot members, a screw secured vertically to the angular foot member, a nut connected to the screw and having a flange thereon, a clamp plate secured for vertical adjustment on the upper portion of the standard and having a stop projection thereon, and an adjustable frame having a head portion pivotally connected to the standard above the clamp plate and supported upon said stop projection, the adjustable frame having two arms provided with bearings to support said pivot screws.

In testimony whereof, I affix my signature on the 23rd day of November, 1923.

GRANT HEEBNER.
